ZERO-SETTING DEVICE FOR CALCULATING MACHINES.

1,413,713.

Specification of Letters Patent. Patented Apr. 25, 1922.

Application filed June 14, 1920. Serial No. 388,852.

To all whom it may concern:

Be it known that I, HUGO ENDERS, a citizen of the Republic of Germany, residing at Lehighton, in the county of Carbon and 5 State of Pennsylvania, have invented certain new and useful Improvements in Zero-Setting Devices for Calculating Machines, of which the following is a specification.

This invention relates to calculating machines, and particularly to devices by which 10 the register or reckoning wheels of a calculator, cash register, or other like machine are returned to zero or "cleared out" after a calculating operation has been performed.

15 The general object of this invention is to provide improved means for this purpose which is of a very simple character, which is positive in its operation, which may be readily applied or used with calculating and like machines of different characteristics, and which may be caused to return all 20 of the digit wheels or reckoning wheels in a series to a zero position by a single actuation of a pivoted lever.

25 A further object is to provide a construction of this character which is extremely compact and in which only a relatively short stroke is required in order to return the digit wheels to their zero position, and in which multiplying gearing is 30 used between the resetting lever and the shaft carrying the digit wheels so as to secure a full and complete revolution of this shaft upon a relatively slight movement of the resetting lever.

35 A further object is to provide a construction of this character which takes up but little room and which is not liable to get out of order.

40 Other objects will appear in the course of the following description.

In the drawings, wherein I have illustrated one practical embodiment of my invention, and in which similar reference characters designate similar parts:—

45 Figure 1 is a perspective view of a calculating machine having my attachment applied thereto;

50 Figure 2 is a vertical sectional view through the movable carriage and housing supporting the number registering wheels, the section being taken on the line 3—3 of Figure 4;

55 Figure 3 is a like view to Figure 2 but showing the resetting handle rotated to re-set the number registering wheels;

Figure 4 is a sectional view on the line 4—4 of Figure 2 showing the number registering wheels in elevation and in section and the end of the housing in section;

Figure 5 is a fragmentary section on the line 5—5 of Figure 4;

Figure 6 is a perspective view of one end of the shaft 12 and the bearing member 14;

Figure 7 is a perspective view of the opposite end of the shaft 12;

Figure 8 is a fragmentary sectional view through shaft 12 and the gear wheel 23 showing a modified arrangement of the spring and pawl therefor.

Referring to these drawings, 10 designates the casing or housing, which is mounted upon a suitable base and which encloses a series of reckoning wheels 11 which are designed to indicate numbers in the problem being calculated. In the ordinary calculating machine there are two series of these wheels indicating respectively one of the factor numbers in the problem to be calculated and the product number. I have illustrated one series of wheels, but it is to 15 be understood that this device is equally applicable to the other series of wheels, or to any construction wherein it is desired to return a series of wheels to a zero position after a differential actuation of the several 20 wheels of the series. The front wall of the casing 10 is provided, as usual, with sight openings through which the numbers on the reckoning wheels 11 may be observed.

The digit or reckoning wheels 11 are 25 loosely mounted for relative rotation on a shaft 12. This shaft at one of its ends is 30 slidably mounted for rotation in a bearing member 13 which is shown as extending upward from the base of the machine, and this shaft 12 projects beyond this bearing member. The opposite end of the shaft 12 35 is mounted in a sleeve bearing 14 which extends through the end wall of the casing or through an indented portion 15 of this end 40 wall, the open end of which may be closed by a plate 16. This sleeve 14 permits longitudinal movement of the shaft 12. The outer end of the bearing sleeve 14 has a 45 notch or recess therein formed with a cam face 17 with which the projecting end of a transverse pin 18 coacts so that as the shaft 12 is rotated in one direction, it will ride 50 up the cam face 17 and as a consequence the shaft will be shifted longitudinally.

55 A spring 12^a acts to shift the shaft 12 55

toward the left in Figure 4, this spring being mounted upon the inner face of the plate 16 and will positively urge the shaft to its initial position immediately upon the completion of a resetting operation.

Each of the reckoning or digit wheels 11 is illustrated as annular in form and attached to one face of each wheel is the toothed disk or gear wheel 19, with which 10 gear wheels or toothed disks the rotation transmitting pinions of the machine engage. To the opposite face of the wheel 11 a metal disk or plate 20 is attached and loosely surrounds the shaft 9. A stud 21 projects longitudinally of the shaft from the inner face of this plate so that in effect this stud 21 is attached to and rotates with the wheel 11, there being one of these studs 21 for each of the wheels 11. On the shaft 12 are provided 20 the spaced studs or teeth 22, which in one position of said shaft are adapted to coact with the respective studs 19 of the wheels 11. These studs 22 are bevelled upon one face. It will be obvious now that in one 25 position of the shaft 12, the studs 22 will be out of engagement with the studs or teeth 20, and that when the shaft is shifted longitudinally to the position shown in Figure 4, the teeth 22 will be in engagement with the studs or teeth 21, and it will be obvious also that this longitudinal shifting of the shaft is secured by the rotation of the shaft 12, which will cause the pin 18 to ride up the cam face 17, and that when this has been 30 achieved, the teeth 21 and 22 will be in engagement with each other and the rotation of the shaft 12 will cause a rotation of all of the wheels 11.

It will be understood that when the wheels 40 11 are in a certain position, namely at zero, each lug 22 will just slide back of the lug 21 when the shaft 12 is rotated and, therefore, not rotate the wheels 11. Only the wheels 11 which are not in zero position when the 45 shaft 12 is rotated will be engaged by the lugs 22 and brought back to zero.

For the purpose of securing this rotation of the shaft 12, I mount loosely upon the shaft 12 a gear wheel 23. The shaft 12 is 50 slidable longitudinally through this gear wheel. This gear wheel is cleft for approximately half its diameter to provide a sector-shaped recess 25 in the periphery of the gear wheel, the bottom of this recess being shown as radial to the center of the shaft and opening, of course, upon the surface of the shaft. The shaft 12 at the point where it is exposed within the groove or recess 25 is formed with a ratchet notch 26, one wall of this notch 55 being radial and the opposite wall extending gradually out to the periphery of the shaft, as illustrated most clearly in Figure 7. Disposed within the recess or groove 25 is a pawl 27 which is substantially right angular 60 in form, and which is pivoted upon a pin 28

extending transversely of the groove adjacent one wall thereof. The free end of this pawl is formed to engage the ratchet tooth 26, and the pawl is urged into this engagement by a spring 29, which at its end remote 70 from the pawl is coiled around a pin 30 extending across the groove or recess 25, the outer extremity of the spring then resting upon the adjacent end wall of this groove. Thus the spring will force the free end of 75 the pawl into engagement with the periphery of the shaft 12 and, of course, into engagement with the ratchet tooth 26 when this ratchet tooth 26 is coincident with the pawl.

Pivotedly mounted upon a pivot pin, shaft or equivalent element 31 is a sector-shaped lever, designated generally 32, which has an upwardly projecting handle 33 which extends out through the slot 34 formed in the 85 face of the housing 10. This lever carries upon one face the arcuate rack 35 having inwardly projecting teeth, and loosely mounted upon a supporting bearing pin 36 is a pinion 37 which meshes with the teeth 90 of the gear wheel 23, but which is slightly smaller in diameter than the gear wheel 23. This pinion is circumferentially grooved, the groove being designated 38, and coinciding with the groove or recess 25 in the wheel 23. 95 The purpose of this groove 38 is to accommodate the pawl 27 when the latter is thrown outward beyond the circumference of the gear wheel 23. The rack 35 meshes with the pinion 37, and this pinion 37 constitutes merely an idler transmitting the motion of the rack to the gear wheel 23, the length of the rack being controlled by the diameter of the gear 23. The lever 32 is urged to its lowered position by means of a 105 spring 39.

It will be obvious now that when the handle 33 is drawn in the direction of the arrow in Figure 2, the rack 35 will cause a rotation of the pinion 37, and this pinion, 110 operating on the gear wheel 23, will cause a rotation of this gear wheel in a clockwise direction and a rotation of the shaft 12 in a clockwise direction. Upon a release of the handle 33 and the downward movement of 115 the arcuate rack 35, a reverse rotation will be communicated to the wheels 27 and 23, but the pawl 27 will ride over the face of the shaft 12 and no reverse rotation will be communicated to the shaft. When the lever 120 32 has arrived in its initial position with the rack stopped from further movement by the base of the machine or by any suitable stop, the pawl 27 will again engage in the notch 26, that is engaged against the ratchet 125 tooth formed by said notch.

The initial movement of the handle 33 in the direction of the arrow will immediately cause a rotation of the shaft 12, which will cause the pin 18 to ride up the cam face 17 130

and this will bring the teeth 22 into engagement with the teeth 21, thus operatively connecting the shaft to the counting or calculating wheels 11 so that all of the wheels will 5 be reversely rotated a complete rotation, which will bring the wheels to a zero position, that is a position in which the zero figure on each wheel will appear at the sight opening in the casing. It will, of course, be 10 obvious that the upward movement of the rack 35 is just sufficient to effect one complete rotation of the shaft 12, at which time the zero figure on the peripheral face of each wheel will appear in the corresponding 15 sight opening. When the pull on the handle 33 is relaxed, the spring 39 will, of course, draw the rack 35 back to its initial position but without affecting the shaft 12. The teeth 21 on the wheels 11 are bevelled on one side 20 and these teeth allow any pin or lug 22 to slip past its corresponding pin or lug 21 if the corresponding wheel 11 is at zero when shaft 12 is rotated, but when a rotation of the shaft is completed, the spring 12^a shifts the 25 shaft axially to its normal position. A coiled spring 29^a may be used in place of the spring 29 illustrated in Figure 5, as shown in Figure 8, the pawl 27^a being changed in form to coact with the coiled or spiral spring 29^a. 30 It is to be noted that the ratchet notch 26 which constitutes a ratchet tooth on the shaft is of sufficient length as to permit the shaft to have longitudinal movement without disconnecting the shaft 12 from its engagement 35 with this pawl. It will be seen that with this construction, the resetting operation may be very quickly effected, as only a single outward movement is necessary on the handle 33 of lever 32. Furthermore, the mounting and 40 arrangement of the several elements within the casing 10 is such as to necessitate no material alterations in the present case construction. The various parts are extremely simple and it is to be particularly noted that 45 they cannot become displaced and will not require frequent repair. Thus the pawl 27 is held from any lateral movement by the side walls of the groove 25. The spring 29 or 29^a is also held from any lateral movement by 50 the side walls of the groove. When the pawl is thrown out and the free end of it rides upon the periphery of the shaft 12, the body of the pawl will project beyond the periphery of the wheel 23, but this projection of the 55 pawl is accommodated by the annular groove 38 in the wheel 37.

It will be seen that the gears 23 and 37 are held securely in place and in proper alignment with each other by being disposed between the wall 13 or bearing member and the lever 32, which, in turn, is disposed against a wall 41 extending upwardly in the case. The rack is relatively wide, as are the gear wheels 37 and 23, so that there is no danger 65 of the teeth breaking either on the rack or the gear wheels. This device obviates the necessity of the usual resetting devices mounted upon the ends of the shaft carrying the reckoning wheels, which constitute an obstruction to the free manipulation of the 70 operating crank or handle whereby the calculating mechanism is actuated, and which furthermore require to be given a number of pulls by the hand in order to secure a full rotation of the shaft 12.

While I have described the application of my device to a calculating machine of a definite character, it will be understood that the parts shown in Figure 1 are merely illustrative of an application of my resetting device 75 and that the present invention is not limited to use in connection with any specific type of machine. It will further be understood that while I have disclosed a preferred embodiment of my construction, yet various changes 80 might be made therein in the form, construction and arrangement of the several parts as may be fairly embodied within the spirit and scope of the invention as claimed.

While I have heretofore described a machine having a single shaft 12 and a single lever 32, these calculating machines are ordinarily provided with two sets of number registering wheels 11, each mounted upon a shaft 12, one shaft being disposed to one side 90 of the middle of the machine and the other at the other side of the middle of the machine. Such an arrangement is illustrated in Figure 1, and in this case there is a separate lever 33 for each series of number registering wheels. Inasmuch as this is a common arrangement of registering wheels in calculating machines of this character, I do not think it necessary to describe this arrangement in detail. Suffice it to say 95 that the shafts 12 which carry the number registering wheels are mounted upon a sliding carriage so that the number registering wheels may be shifted with relation to the actuating wheels which, when shifted, 100 rotate the number carrying wheels or disks 11.

I claim:

1. A mechanism including a shaft, a wheel loose on the shaft, the wheel having a recess extending through it from the exterior of the wheel parallel to the sides of the wheel and intersecting said shaft; a pawl carried in the recess and pivoted to the wheel and engaging the shaft upon a rotation of the wheel in one direction but riding freely over the shaft upon a rotation in the other direction, and actuating means operatively connected to said wheel to rotate it.
2. A mechanism including a shaft, a gear wheel loose on the shaft and having a groove extending inward from the exterior of the wheel parallel to the sides of the gear wheel and intersecting the shaft, a pawl carried in the said groove and held from lateral move-

1. In a calculating machine, a rotatable and axially movable shaft, a series of digit wheels loosely mounted on the shaft, the wheels and the shaft having means to coact in one position of said shaft and cause a rotation of the wheels with the shaft, a resetting means for the digit wheels including means operable upon an initial rotation of the shaft for imparting a limited axial movement thereto to position the coacting means on said shaft and the digit wheels into operative engagement with each other.
2. In a calculating machine, a rotatable and axially movable shaft, a series of digit wheels loosely mounted on said shaft, the wheels and shaft having means to coact in one position of said shaft and cause the rotation of said wheels with the shaft, a resetting means for the digit wheels including a gear wheel loosely mounted upon the shaft and through which the shaft slides, means for operatively engaging the gear wheel with the shaft upon a rotation of the gear wheel in one direction but operatively disengaging the gear wheel from the shaft upon a rotation of the gear wheel in the opposite direction, said means acting in all axially adjusted positions of the shaft, a pinion engaging said gear wheel, a manually shiftable rack engaging said pinion, and means operable upon such rotation of the shaft for initially imparting a limited axial movement thereto to position the coacting means on said shaft and the digit wheels into operative engagement with each other.
3. In a calculating machine, a rotatable and axially movable shaft, a series of digit wheels loosely mounted on the shaft, the wheels and the shaft having means to coact in one position of said shaft and cause a rotation of the wheels with the shaft, a resetting means for the digit wheels including means operable upon an initial rotation of the shaft for imparting a limited axial movement thereto to position the coacting means on said shaft and the digit wheels into operative engagement with each other.
4. In a calculating machine, a rotatable and axially movable shaft, a series of digit wheels loosely mounted on the shaft, the wheels and the shaft having means to coact in one position of said shaft and cause a rotation of the wheels with the shaft, a resetting means for the digit wheels including means operable upon an initial rotation of the shaft for imparting a limited axial movement thereto to position the coacting means on said shaft and the digit wheels for operative engagement with each other, said shaft at one end being formed with a longitudinally extending ratchet notch, a gear wheel loosely mounted on the shaft over said ratchet notch and through which gear wheel the shaft is axially movable, said gear wheel being held from axial movement with the shaft and being formed with a recess extending inward from the peripheral face of the gear wheel and intersecting the shaft, a pawl pivotally mounted in said recess and coacting with the notch in the shaft in all axially shifted positions of the shaft, a spring disposed in said recess and urging the pawl into engagement with the shaft, a pinion engaging the first named gear wheel and having a circumferential groove to accommodate the projection of said pawl when it is shifted outward, and a pivoted lever having an arcuate rack engaging the pinion and having a handle whereby the lever may be manipulated.
5. In a calculating machine, a rotatable and axially movable shaft, a series of digit wheels loosely mounted on the shaft, the wheels and the shaft having means to coact in one position of said shaft and cause a rotation of the wheels with the shaft, a resetting means for the digit wheels including means operable upon an initial rotation of the shaft for imparting a limited axial movement thereto to position the coacting means on said shaft and the digit wheels for operative engagement with each other, said shaft at one end being formed with a longitudinally extending ratchet notch, a gear wheel loosely mounted on the shaft over said ratchet notch and through which gear wheel the shaft is axially movable, said gear wheel being held from axial movement with the shaft and being formed with a recess extending inward from the peripheral face of the gear wheel and intersecting the shaft, a pawl pivotally mounted in said recess and coacting with the notch in the shaft in all axially shifted positions of the shaft, a spring disposed in said recess and urging the pawl into engagement with the shaft, a pinion engaging the first named gear wheel and having a circumferential groove to accommodate the projection of said pawl when it is shifted outward, and a pivoted lever having an arcuate rack engaging the pinion and having a handle whereby the lever may be manipulated.
6. In a calculating machine, a rotatable and axially movable shaft, a series of digit wheels loosely mounted on said shaft, said wheels and the shaft having means to coact in one position of said shaft and cause a rotation of the wheels with the shaft, means for causing an axial movement of the shaft in a direction to cause the engagement of said digit wheels with the shaft including a cam and a member engaging the cam and bearing thereon and carried by the shaft, and means for rotating said shaft in one direction including a gear wheel loosely mounted on the shaft and in which the shaft is slidingly mounted, means carried by said gear wheel for engaging the shaft for common rotation upon a movement of the gear wheel in one direction but said gear wheel moving freely upon the shaft upon a rotation of the gear wheel in the other direction, said means being disposed within the gear wheel, and an actuating lever operatively engaging said gear wheel to cause its rotation in either direction, and means yieldingly urging said lever to an initial position.

In testimony whereof I affix my signature.
HUGO ENDERS.
